PRESSURE AND TEMPERATURE RESPONSIVE FUEL METERING AND INJECTION PUMP

Caleb E. Summers, Orchard Lake, Mich.

Application August 14, 1943, Serial No. 493,699

4 Claims. (Cl. 123—139)

1
The present invention relates to multicylinder internal combustion engines, and more specifically to means for supplying fuel to the several cylinders.

As is well known, the supplying of fuel to engines from a conventional carburetor may be accompanied by a number of difficulties such as unequal distribution, mixture variation due to changes in temperature and barometric pressure and others.

It is among the objects of the present invention to overcome such difficulties by providing means for supplying fuel to the individual cylinders by injection of finely atomized liquid fuel under high pressure and automatically varying the amount of injected fuel in accordance with load, temperature and barometric pressure.

Another object is to provide a fuel metering means which provides substantially equal distribution to the several cylinders.

Another object is to provide fuel supply means which automatically adjusts the amount of fuel atomized into the cylinders to accord with the amount of air admitted thereto.

Another object is to provide a fuel metering means which imposes no restriction on the incoming air charge.

Another object is to provide a fuel supply pump in which the body may be made of a material having a high coefficient of expansion and plungers of a material having a relatively low expansion rate, so constructed that extreme variations in temperature do not substantially change the clearance between the plunger and its sleeve.

Another object is to provide a high pressure fuel pump in which oil pressure lubrication is maintained around the plungers.

Still another object is to provide a fuel pump in which the clearance between the plunger and the bore is automatically generated by forcing a plunger into a slightly undersized soft-metal lined bore.

Other objects and advantages will be apparent to those skilled in the art upon reference to the following description and the accompanying drawings in which

Figure 1 is a side elevation, partly in section, of a fuel pump constructed in accordance with the present invention.

Figure 2 is a top plan view of the same with part of the cover broken away.

Figure 3 is an end elevation thereof.

Figure 4 is a section on line 4—4 of Figure 1 of a part of the cam shaft.

2
Figure 5 is a detail view of the bellows-actuated shaft.

Figures 6 and 7 show respectively a side elevation and a section of a preferred cam construction for large units.

In the drawings, the fuel pump is indicated as consisting of a closed casing of two parts, the lower portion 10 housing some of the working parts and the upper portion comprising a pair of cylinder blocks 11 and 11A, and a sealing cover 12, and having the other working parts.

The cylinder blocks, each containing one half the number of pump cylinders, are shown oppositely arranged in the same plane, so that the 15 pistons for all of the cylinders may be actuated from a single actuating shaft. It will be understood that to adapt this device to various motors and services, the pump cylinders here shown opposed, may be arranged in line in V form or radial.

Only one cylinder and piston is shown in detail, but any desired number may be used, depending upon the number of engine cylinders to be served. In the present instance, the number 20 of outlets shown in Figure 2, indicates a total of twelve.

As shown in Figure 1, each of the cylinders 15 is lined with a sleeve 16 provided with annular reliefs 18 on the inside and pressed into place in the casing 11. The arrangement of the reliefs 17 and 18 in staggered relation and slightly overlapping as shown, permits the use of a ferrous metal for the piston and sleeve and a body of a light alloy of a much higher coefficient of expansion, and still maintain the small piston clearance even under extreme temperature changes. The outer ends of the cylinders 15 are shown as being closed by a cylinder head 20 providing for each cylinder a pump chamber 21 into which fuel is drawn from a common supply 22, past a disc valve 23 tensioned against its seat by a suitable spring 24. From the chamber 21 the fuel is forced through outlet 25 controlled by valve 26, the latter being resiliently held in its seat by a suitable spring 27.

Operating in each of the cylinders 15 or more correctly, sleeve 16, is a piston 30, and since a minimum clearance between cylinder and piston must be had, it is preferred to coat, preferably by plating, the inside of the sleeve with a relatively soft bearing metal such as cadmium, tin or silver, to provide an inside diameter a few tenths of a thousandth of an inch less than the diameter of the piston. It should be understood, of course, that the piston should be polished and

straight, so that when forced into the plated sleeve, a substantially perfect fit is obtained.

For each of the pistons 30 is provided a rather strong spring 31, suitably anchored to a stationary part of the cylinder block and biased to move the piston on its outward or intake stroke, while the rearward end of each piston 30 is provided with a roller 32 cooperating with a cam 33 during the inward or pumping stroke, the cam providing the actuating force.

The cams 33 are fixed to a shaft 35 shown in Figure 1 as tubular, said shaft being supported by suitable bearings 33A, Fig. 2, said shaft being driven at half engine speed (by suitable means, not shown) and mounted between the cylinder blocks 11 and 11A, each cam actuating a piston 30 in one cylinder of block 11 and one in the aligned cylinder in block 11A.

The cams 33 are of course so located radially upon the shaft 35 and the pump outlets 25 so connected as to accord with the firing order of the engine.

The mechanism thus far described, in its actuation, will deliver at each of the strokes of the pistons, maximum amounts of fuel, so in order to vary the delivery, the pump is provided with means for varying the length of piston stroke and such means, in the present invention, is also constructed and arranged to cause such variation in accordance with the engine load and also in accordance with variations in temperature and pressure.

This varying or regulating means is shown in Figures 1, 2 and 4, and consists of a pair of other cams 40, 41, arranged adjacent each of the cams 33 and movable around shaft 35 so as to block at the proper point the movement of the pistons 30 outward of the cylinders on their intake stroke, the shoulder 30A contacting the cam 41, at any point from no stroke to full stroke, depending upon the angular position of cam 41. Thus an amount of fuel less than the maximum is drawn into the cylinder, at the point at which the piston movement is arrested and consequently the incoming fuel charge, being determined by the conditions of load, temperature and pressure existing at the time. These other cams are mounted loosely on the shaft 35 and are shown at 40 and 41 for a cam 33, a second pair 42 and 43 being indicated for a second cam 33 (see Fig. 4).

Each of the cams 40 to 43, consists of a cam portion and a bearing portion 40A to 43A (see Fig. 4) and on each cam portion is provided an ear 40B.

Surrounding the bearing portions 40A, etc. is a sleeve 45 carrying at each end a pair of arms 45A and 45B, each carrying an ear 45C, and a second pair of arms 45D and 45E, each of which carries a stop lug 45F. The ears 40B and 45C extend outwardly from the cams 40 and 41 and serve as abutments for springs 46 which hold the cams 40, etc. resiliently against the stops 45F. Thus it will be seen that when there is a sudden demand for power, the bellows easily rotates the cams 40-41, etc. even though some are acting on the plungers, for the movement is "down hill." When less power is needed, the bellows takes a position compressing the springs 46 until the cam 33 lifts the plungers.

As may be noted from Figure 4, a single sleeve 45 is arranged to coat with the movable cams 40, etc. for two of the cams 33. This means that, in the pump illustrated with twelve cylinders, there will be three sleeves 45.

Each of the three sleeves 45 is provided with

an actuating arm 50 and each arm 50 connected by a suitable link 51 to a crank arm 52 fixed upon a rotatable shaft 53. The shaft 53 is in turn rotatable through arms 54 connected through link 55 to the bellows 60, of which two are shown, but it should be understood that one or several may be used without departing from the invention.

The sealed bellows 60 is mounted within the lower part of the housing 10 and is filled with an inert gas. In order to make the bellows more sensitive to outside temperatures and also to reduce the volume of its gas contents so that the maximum expansion will not overstrain the metal of the bellows a cylindrical displacement member 61 is used to seal the bellows. This member 61 is integral with the base 62 of the sealed bellows 60 and is sufficiently large to substantially fill the bellows, leaving only the bellows ribs and a small part of the remaining interior for the inert gas.

The member 61 is of course closed at its inner end but is open at the outer end and thereby provides a large surface susceptible to the influence of outside temperatures and, since the sealed in gas is dispersed in a thin layer on the outside of member 61, it receives and reacts quickly to any temperature change outside or inside of housing 10.

30 The bellows 60 is mounted in the housing 10 in a cylindrical guide 63 and since the housing is filled with oil, well above the guide, the latter is perforated as shown, to permit free movement of the bellows. Further in order to protect the bellows against wear, bearing rings 64 may be provided.

35 In order to submit the bellows 60 to the influence of load conditions, the housing 10 is, as stated above, sealed and provided with a nipple 70 or other connecting means whereby the interior of the housing may be connected to the intake manifold of the engine.

40 In the operation of the device, when the conditions of load and temperature indicate a full charge of fuel in the respective cylinders of the engine, the cams 40 and 41, and the corresponding cams will be in approximately the position shown in Figure 1, that is, they will not interfere with the movement in and out of the pistons 30.

45 Consequently, each piston 30 draws in and forces out a full charge. When, however, a part throttle and a high outside temperature, or either condition exists, the bellows 60 will expand and move the cams 40, 41, etc. into position to block more or less the outward movement of pistons 30 with a consequent pumping of only a part charge of fuel.

50 It is now apparent that the inert gas sealed within the bellows 60 is subjected to the same temperature and absolute pressure as the charge entering the cylinder and therefore its density is proportional to the density of the air charge. If, therefore, we have a measure of the volume of charge entering a cylinder, the position of the bellows acting through selected lever ratios and a proper contour of cams 40-41 could be made to control the stroke of the plunger 30, to give the desired fuel (including required variables as rich at full load and lean at part load).

55 While the piston displacement is definite, the volume of gases drawn in per stroke varies with atmospheric pressure changes owing to the behavior of the residual gases in the combustion chamber. To compensate for this variable, the sealed bellows 60 is mounted on a short open

bellows 60A, the bellows 60A being controlled in its axial expansion by the relatively stiff coiled spring 62A. The bellows 60A is subjected on the outside to the pressure of the manifold, which may vary from 10 inches mercury to more than 70 inches. The bellows is subjected on the inside to air pressure which may vary from 31 inches of mercury to 8 inches. A proper selection of the rate of the spring 62A, provided with proper stops or controls, will give a closely approximate correction for the variation in volumetric efficiency of an airplane engine from closed throttle to full supercharge and from sea level to the stratosphere.

Since the method of controlling the rate of fuel discharge is by arresting the pump plunger at any required point in its intake stroke, it is desirable to make the contour of the cam 33 such that the velocity of the plunger 30 is substantially uniform throughout the stroke so the shock of such arrest and also the shock when the cam 33 again contacts the roller 32 for the discharge stroke, will be uniform and at a minimum.

In order to cushion such shock, a slight resilience may be provided by making the cams 33 in the form shown in Figures 6 and 7, that is, by forming the cams of sheet metal so that the cam surface is on an overhanging flange capable of a slight "give." The uniform speed of the plunger and the sudden stop at the end of the stroke, gives uniform atomization and a minimum drool.

The relative proportion of the 360° of the cam 33 that are used for the maximum discharge stroke and the maximum intake stroke of the plunger 30 is to be determined for best results in each service. Preferably the discharge stroke shall not be more than 120° which leaves 240° for the intake stroke which is relatively slow and easy for the fuel to follow.

It should be noted that with the extremely small clearance of pistons 30, very high pressures will be developed in the fuel delivery to the atomizers in the several cylinders and in order to lubricate the pistons and further seal the pistons, oil under high pressure may be forced into the central relief 18 through the inlet 16K.

It should further be noted that due to the slope of the cams 40, 41, etc., they will have a tendency to move to full charge position and, therefore, the direction of rotation of shaft 35 should be such as to tend to neutralize this by the friction of the parts.

One of the many advantages to be derived from the use of the present device lies in the fact that it acts also as a timer for the fuel injection. When

the parts are in position to supply a partial charge, the injection is somewhat delayed and such delay favors stratification, and thereby facilitates firing of the lean charge.

5 I claim:

1. In a fuel metering and injection pump, a housing enclosing the same, and adapted to contain a body of oil, and means in said housing for varying the discharge from said pump, said means including a sealed fluid filled bellows fixed at one end to a wall of said housing and submerged in said oil, and guide means for said bellows, said guide means being perforated to permit free movement of said oil to and from the bellows, and a tube extending through said wall into said bellows and having its inner end closed and its outer end open, whereby to make more immediate the effect of the temperature of the outside air on said bellows and fluid content.

10 2. In fuel injection means for an internal combustion engine including a variable stroke pump and cam means for varying said stroke, governor means for said cam means including a sealed housing, means for subjecting the inside of said housing to the pressure conditions of the intake manifold of said engine, a body of oil in said housing, an expandable and contractible element submerged in said oil, in said housing, and adapted to actuate said cam means, means for subjecting said element to temperature outside of said housing, and means to position said element in accordance with surrounding atmospheric pressure.

15 3. In fuel injection means for an internal combustion engine including a variable stroke pump and cam means for varying said stroke, governor means for said cam means including a sealed housing, means for subjecting the inside of said housing to the pressure conditions of the intake manifold of said engine, a body of oil in said housing, an expandable and contractible element submerged in said oil, in said housing, and adapted to actuate said cam, and means for subjecting said element to temperature outside of said housing.

20 4. In fuel injection means for an internal combustion engine including a variable stroke pump and cam means for varying said stroke, governor means for said cam means including a sealed housing, means for subjecting the inside of said housing to the pressure conditions of the intake manifold of said engine, a body of oil in said housing, an expandable and contractible element submerged in said oil, in said housing, and adapted to actuate said cam, and means for subjecting said element to temperature outside of said housing.

25 5. In fuel pump regulating means for internal combustion engines, a fluid filled bellows element operatively connected to said pump to vary the delivery thereof, means for subjecting the outside of said bellows to intake manifold pressure to thereby tend to increase the pump delivery, means to subject the inside of said bellows to atmospheric temperature, and means whereby to subject a portion of said bellows to atmospheric pressure.

CALEB E. SUMMERS.
